UNITED STATES PATENT OFFICE.

WILLIAM MUMBRAUER, OF NEW YORK, N. Y.

DOOR-LOCK.

1,324,018.

Specification of Letters Patent.

Patented Dec. 2, 1919.

Application filed May 13, 1919. Serial No. 296,804.

To all whom it may concern:

Be it known that I, WILLIAM MUMBRAUER, a citizen of the United States, and a resident of the borough of the Bronx, city and State of New York, have invented certain new and useful Improvements in Door-Locks, of which the following is a specification.

This invention relates to door closures and has for an object to provide an improved bolt which will be readily released under certain conditions.

The invention provides a bolt particularly adapted for use upon emergency exit doors of theaters, churches, factories, and the like. 15 This application is in part a continuation of applications, Serial No. 268,448 filed December 27, 1918, and Serial No. 268,449, filed December 27, 1918.

Referring to the accompanying drawing 20 forming part hereof, and in which I have shown an illustrative embodiment of the invention:

Figure 1 is a horizontal, sectional view of a bolt constructed in accordance with the 25 invention applied to a double door. The dotted lines show the leaves of the door in partly opened position;

Fig. 2 is an enlarged view of the device, 30 the left-hand leaf, which carries the keeper, being shown in its final position and the right-hand leaf which carries the bolt being shown in closing position;

Fig. 3 is a view in elevation, the parts 35 being shown in the same position as in Fig. 2;

Fig. 4 is a section taken on line 4—4, Fig. 2, showing the parts in locked relation;

Fig. 5 is a section taken on the same line 40 showing the parts in unlocked relation;

Fig. 6 is an inverted longitudinal section 45 taken on line 6—6, Fig. 4;

Fig. 7 is a vertical longitudinal section 50 of a portion of the device taken on line 7—7, Fig. 5;

Fig. 8 is a section on line 8—8, Fig. 7;

Fig. 9 is a partial view of the casing and the bolt, certain parts being omitted, taken on the line 9—9, Fig. 7; and

Fig. 10 is a plan view showing a bolt 55 constructed in accordance with the invention applied to a single door.

The bolt construction shown for the purposes of illustrating the invention, comprises a sliding bolt, locking means for holding the bolt in projected position and a re-

leasing means arranged to unlock the bolt upon being pressed toward the door.

Referring to Figs. 1 to 9 in which the device is illustrated as applied to a double door, the bolt 1 is carried by one door leaf, 60 2, and is projected against a keeper 3 carried by the companion door leaf 4 in such manner that the thrust of the bolt against the keeper tends to prevent outward movement of the door leaves. The bolt is positioned to engage the keeper at a point offset inwardly from a line connecting the two 65 hinges so that the bolt exerts a considerable force to hold the door leaves in closed position. As shown, the bolt consists of a tube 70 6 in the forward end of which is secured a head 7 which head is preferably tapered as shown in Fig. 6 to provide a reduced and rounded end. A casing 8 secured in brackets 9 and 10 affixed to the door leaf provides support for the bolt. Preferably the bracket 9 is longer than the bracket 10 to 75 position the keeper-engaging end of the bolt away from the doors thereby to increase the holding power of the device. The bracket 80 10 is formed to close the end of the casing and provide an abutment 11 for a compression spring 12 which normally holds the bolt in projected position.

The locking means shown consists of a 85 sleeve 14 rotatably mounted upon the casing, provided with an upstanding lug or handle 15 and having locking connection with the bolt 1 through a transverse slot 16 in the casing by means of a pin 17 secured 90 to the locking sleeve and projected inwardly through the slot 16 and into a bayonet slot 18 in the bolt. The transverse portion of the bayonet slot may be made wider than the pin to provide a limited freedom of 95 movement of the bolt when locked. When the locking pin 17 is in the outer end of the transverse portion of the bayonet slot as in the position of parts shown in Figs. 4 and 6, the bolt is locked against retraction 100 but when the pin is in the inner end of the transverse portion and in line with the longitudinal portion of the bayonet slot, as occurs when the sleeve handle 15 is pushed toward the door as in the position of parts 105 shown in Figs. 5 and 9, the bolt may be retracted by pressure longitudinally against the end thereof.

In operation, the locking member may 110 be moved to locking and unlocking position

by engaging the handle 15. It is desirable, however, to provide a separate releasing member for moving the locking member to unlocking or releasing position. The releasing member 20 is more conveniently accessible than the handle 15 and so positioned that in the event of a panic the pressure of a crowd toward the door will necessarily move said releasing member to release the lock, permitting the doors to be opened, but when the releasing member is grasped to pull the open door closed the bolt is not thereby locked in projected position as would be the case if the handle 15 were so grasped and pulled. As shown, the releasing member 20 comprises a manipulating rail 21 and bearing sleeves 22, 22, rotatably mounted upon the supporting casing and provided with a cross bar 23 positioned to engage against the outer face of the locking member handle 15. Downward and outward movement of the releasing member is limited by suitable means as, for example, by chains 25, 25, secured thereto and to the door.

In operation, pressure against the manipulating rail 21 toward the door will rotate the releasing member and therefore locking member to releasing position but a pull upon the same releasing member will not again move the locking member to locking position. To lock the bolt it is necessary to engage the locking member itself and pull it to locking position.

Suitable means is provided to prevent rotation of the bolt within the casing. In the particular construction shown, a slot 27 is provided in one side near its forward end and a screw 28 extends through both the bracket 9 and casing 8 and projects into such slot, thus holding the casing in position in the bracket and preventing rotation of the bolt. Means to prevent accidental rotation of the locking member may be provided, as, for instance, a spring detent 29 mounted in the locking member and engaging two recesses 30, 31, in the casing so positioned that the locking sleeve is releasably retained in either of the extreme positions. The keeper 3 is formed to provide a pocket 32 spaced from the face of the door leaf to receive the end of the locking bolt. This keeper may conveniently be formed with a handle 33 for convenient operation of the door. A cover strip 34 may conveniently be provided upon the outer face of and overlapping the edge of the door leaf to which the lock is attached. Ordinarily the doors will be drawn to closed position by drawing both doors inwardly at the same time, the projected end of the spring pressed bolt being positioned in the recess or pocket of the keeper as soon as the doors are near enough to closed position to permit this to be done. It is desirable, however, to make provision whereby in the event the door leaf to which the

keeper is attached is in closed position the other door leaf may be drawn to closed position without the necessity for opening the first leaf. Accordingly in the construction illustrated the keeper is shown as provided with a latch plate 36 projecting outwardly across the edge of the door.

In the construction shown in Fig. 10 in which is shown a locking bolt constructed in accordance with the invention applied to a single leaf door, the construction of the bolt and associated parts is similar to the construction previously described except that the casing is secured to the door leaf by two brackets 9', 10' of the same size designed to hold the device parallel to and relatively close to the door leaf. The bolt is so positioned on the door that in projected position it will clear the door jamb as the door is opened and closed. The keeper consists of a roller 34 rotatably mounted upon the vertical pin 35 in the door jamb and positioned to project into the path of movement of the end of the bolt whereby the door is held in closed position when the bolt lies back of the roller and is locked in projected position and whereby the bolt when unlocked is retracted as the door is swung to move the bolt past the roller.

Various changes may be made in the details of construction without departing from the scope of the invention as set forth in the appended claims.

I claim:

1. A door closure comprising a slotted casing, an inclosed bolt, a sleeve co-axial with and axially rotatable on the casing, and a member on said sleeve that projects through said casing into engagement with said bolt.

2. A door closure comprising a slotted casing, an inclosed spring bolt having a bayonet slot, a sleeve axially rotatable on the casing, and a member on said sleeve that projects through said casing into engagement with said bayonet slot.

3. A door closure comprising a slotted casing, an inclosed spring bolt, a sleeve co-axial with and axially rotatable on the casing, a member on said sleeve that projects through said casing into engagement with said bolt, said sleeve having a handle projecting therefrom.

4. A door closure comprising a slotted casing, an inclosed bolt, a concentric sleeve axially rotatable on the casing, a member on said sleeve that projects through said casing into engagement with said bolt, and an abutment adapted to operatively engage the free end of the bolt.

5. A door closure comprising a pair of hinged door leaves, a bolt carried by one of said leaves, means for locking and unlocking said bolt in its advanced position, and a stop on the second leaf, which is adapted to

- operatively engage the working end of the bolt, and to retract said bolt at the opening of the door. 35
6. A door closure comprising a pair of hinged door leaves, a casing carried by one of said leaves, a bolt slidable therein, a member rotatable on the casing, means on said member for locking and unlocking said bolt in its advanced position, and a stop on the second leaf, which is adapted to operatively engage the working end of the bolt, and to retract said bolt at the opening of the door. 40
- 10 7. A device of the character described comprising a casing, a bolt slidable therein, a sleeve axially rotatable on the casing and having locking engagement with said bolt to hold the same in projected position, and a releasing member operable by pressure thereagainst to release said bolt, substantially as described. 45
- 15 8. A device of the character described comprising a slotted casing disposed at an angle to the face of the door, a spring bolt slidable therein, a sleeve co-axial with and axially rotatable on the casing connected with said bolt through a slot in the casing and operative to lock the bolt in projected position. 50
- 20 25 9. In a device of the character described, the combination with a pair of door leaves of a keeper secured to one door leaf, a bolt carried by the other door leaf and projected longitudinally against said keeper, and co- 55
- operating therewith when in projected position to hold the door leaves in closed relation, and means operative to hold the bolt in projected position to hold the door leaves in closed relation but operative upon pressure thereagainst toward the door to permit retraction of the bolt and opening of the door leaves, substantially as described. 60
- 10 15 20 25 30 35 40 45 50 55 60 65
10. In a device of the character described, in combination, a bolt, a support in which said bolt is slidably mounted, a locking member mounted on said support and movable in a plane transverse to said bolt to hold said bolt in operative position, a releasing member mounted on said support for movement independently of the bolt and locking member in a plane transverse to said bolt and operable to release the locking member. 50
11. In a device of the character described, the combination with a door of a bolt carried thereby, a locking member carried by said door and movable in a plane transverse to said bolt to lock said bolt in operative position and a releasing member movable in a plane transverse to said bolt operative when moved in one direction to release said bolt and movable in the opposite direction independently of the bolt and locking member and inoperative when so moved to lock said bolt. 60
- 65
- In testimony whereof I have hereunto set my hand.
- WILLIAM MUMBRAUER.
